Ex. No.	Amine	Salt	Method of preparation	Solvent
6	p-Aminobenzoic acid	N-methyl piperidinium	Via free acid	Benzene.
7	do	Tetramethylhydrazinium	do	Toluene.
8	do	Morpholinium	do	Do.
9	do	Ethyltrimethylammonium	do	Do.
10	do	Ethylammonium	do	Do.
11	do	Triethylammonium	Direct (see Ex. 6)	Ethanol.
12	do	N-methyl-O-methylhydroxylammonium	Via free acid	Toluene.
13	do	Magnesium	do	Water.
14	do	Calcium	do	Do.
15	do	Diethylammonium	do	Toluene.
16	do	t-Butylammonium	do	Do.
17	do	Tetramethylammonium	do	Do.
18	Anthranilic acid	Diethylammonium	do	Do.
19	do	Strontium	do	Water.
20	do	N,N'-diethylpiperazinium	do	Toluene.
21	do	DimethylPhenylhydrazinium	do	Do.
22	do	Barium	do	Water.

We Claim:

1. A primary, secondary or tertiary lower alkyl amine salt of N-(2-carboxyphenyl) leucauramine or N-(4-carboxyphenyl) leucauramine.
